UNITED STATES PATENT OFFICE.

RUSSELL P. SCHUYLER, OF CHICAGO, ILLINOIS.

LUBRICATING DEVICE.

1,216,505.

Specification of Letters Patent. Patented Feb. 20, 1917.

Application filed January 19, 1916. Serial No. 72,996.

To all whom it may concern:

Be it known that I, RUSSELL P. SCHUYLER, a citizen of the United States, residing at Chicago, in the county of Cook and State of Illinois, have invented certain new and useful Improvements in Lubricating Devices, of which the following is a description.

My invention belongs to that general class of devices intended for use in lubricating moving parts, having impulsive or vibrating action, and particularly in which the movement and operation of the lubricating device are practically automatic. To this end my invention consists of the novel construction, arrangement and combination of parts herein shown and described, and more particularly pointed out in the claims.

In the drawings, wherein like reference characters indicate like or corresponding parts,

Figure 1 is a vertical section through one form of my device;

Fig. 2 is a section thereof on line 2—2 of Fig. 1;

Fig. 3 is a similar section on line 3—3 of Fig. 1;

Fig. 4 is a similar section on line 4—4 of Fig. 1;

Fig. 5 is a section on line 5—5 of Fig. 1;

Fig. 6 is a vertical section of a slightly modified form of my improved device;

Fig. 7 is a section taken substantially on line 7—7 of Fig. 6;

Fig. 8 is a section taken on line 8—8 of Fig. 6, and

Fig. 9 is a section taken substantially on line 9—9 of Fig. 6.

In the drawings, 1 indicates a lubricator cup provided with a vertically adjustable stem 2 carrying on its lower end a needle valve 3, controlling the passage of a lubricant through a duct 4 to the chamber 5. The chamber 5 is provided with a suitable valve seat 6, and the reduced portion 7 extends from the valve seat into the enlarged sight chamber 8. At the lower end of the chamber 8 an upwardly seating valve seat 9 is provided, formed on the upper face of the chamber 10, the lubricant passing from the chamber 10 through the various openings 11 into the conducting pipe 12. A peculiarly shaped conical part 13 has adjustably connected to its upper part a valve 14, provided with a seat 15, coöperating with the valve seat 6. A neck 16 connects the valve

14 to the part 13, as shown. A second conical valve 17 has a seat 18 coöperating with the valve-seat 9 of the chamber 10. The part 13 and the valve 17 are suitably connected, as for illustration by rods 19. Suitable downwardly extending apertures 20 on the upper surface of the part 13 cause the lubricant to flow down to the point on the part 13, and from thence drop downward in view through the sight openings upon the valve 17. In the preferred construction a wall or rim 21 is raised about the upper face of the part 13, so that as the lubricant drops down thereon from the walls of the throat 7, it will be confined to the upper face of the part and pass through the openings 20, as stated. The valve 14 is preferably made substantially like an ordinary screw, having screw-threaded connection at its lower end with the part 13, whereby it may be longitudinally adjustable in relation to said part, as desired.

Fig. 6 shows a slightly modified form of my improved device, in which the receptacle is provided with an air tube 22, which at the lower end connects with the duct 23, which reaches to the chamber 8, while the valve 24 corresponding to the valve 17 in Fig. 1, is provided with one or more apertures 25, permitting the air to pass therethrough. It will thus be seen that as the device is operated, provision is made for the passage of a certain quantity of air to prevent a partial vacuum in the cup 1, or other part, which might in some cases interfere with steady and regular operation of the device. In both cases I prefer to use a removable plate 26 below the valves 9 or 24, as the size and number of openings therethrough tend to regulate the vaporization of the lubricant as delivered, as well as the admission of air to the device. Thus a plurality of such plates may be provided with a varying of apertures therein, and of varying sizes, and the particular plate used that may be found most satisfactory.

Fig. 2 illustrates the manner in which the oil is admitted to the valve in the form shown in Fig. 1. Fig. 9 shows the parts where the valve 24 is provided with openings 25 therethrough, as stated. The mode of operation is apparent. Gravity causes the valve 14 to be normally seated, and to prevent the passage of the lubricant thereby. The impulses of the coöperating part to

which the lubricator is attached causes the valve to be slightly lifted at each operation, permitting a small quantity of the lubricant to pass by the valve 14, and thence down part 13, dropping upon the top of the valve 17. Here it is distributed, owing to the conical shape of the valve into a thin film, and is thence conducted through the apertures 11 in the part 26. As stated, these apertures 10 may be of any number desired. In some cases, as when in use upon a vacuum pump, it may be desirable to regulate the passage of the fluid therethrough, thereby to a greater or less extent controlling the vaporizing of the film or oil as it is delivered to said part. The valve 14 being adjustable in relation to the part 13, the needle valve 3 being also adjustable, it is obvious that the quantity of the fluid passing through the 20 valve can be readily regulated as desired.

The device being once adjusted to the co-operating machine, it is not necessary to manipulate valves when the machine is stopped. In practice it is found that the device is substantially automatic in this respect.

Having thus described my invention, it is obvious that various immaterial modifications may be made without departing from the spirit of my invention; hence I do not 30 wish to be understood as limiting myself to the exact form, construction, arrangement or combination of parts herein shown and described, or uses mentioned.

What I claim as new and desire to secure 35 by Letters Patent is:—

1. A lubricating device comprising a suitable receptacle, having formed therein a duct, a chamber below the duct, and a second chamber below the first, with a reduced 40 passage connecting the two, each of said chambers having a valve seat formed therein, and means for controlling the passage of fluid through the duct, in combination with a valve coöperating with the valve seat in the first chamber, provided with a stem passing through the reduced passage, a conical part located in the second chamber adjustably secured to the valve, a valve arranged to coöperate with the valve seat in 45 the second chamber, and means for connecting the conical part with said second part, whereby the two valves form a unitary structure and operate in unison.

2. A lubricating device comprising a suitable receptacle having formed therein a duct, a chamber below the duct, and a second chamber below the first, a reduced passage connecting the two, each of said chambers having a valve seat formed therein, and 50 an adjustable valve controlling the duct, in combination with a valve arranged to co-operate with the valve seat in the first chamber, provided with a stem passing through the reduced passage, a conical part located 55 in the second chamber secured to the valve,

a valve arranged to coöperate with the valve seat in the second chamber, and means for connecting the conical part to said second valve, whereby the two valves form a unitary structure and operate in unison.

3. A device of the kind described comprising a suitable receptacle having a duct formed therein, a valve controlling the duct, a detachable part provided with a chamber arranged below the duct, a second chamber 70 arranged below the first, with a reduced passage connecting the two, each of said chambers having a valve seat formed therein, in combination with a valve having a seat arranged to coöperate with the valve seat in the first chamber, a stem passing through the reduced passage, a conical part located in said second chamber and connected to the stem, a valve arranged to coöperate with the valve seat in the second chamber, means 75 for connecting the conical part and the second valve, whereby the two operate in unison, and means for preventing a partial vacuum in the receptacle as the lubricant is withdrawn.

4. A device of the kind described comprising a suitable receptacle, having a duct formed therein, a valve controlling the duct, a downwardly extending part provided with two chambers, one arranged below the other, 80 the two being connected by a reduced passage, each of said chambers having a valve seat formed therein, in combination with a valve having a seat arranged to coöperate with the valve seat in the upper chamber, 85 provided with a stem passing through the connecting passage, a conical part located in the lower chamber and connected to the stem, a valve arranged to coöperate with the valve seat in the lower chamber, means for connecting the conical part to said lower valve, whereby the two valves operate in 90 unison, and means for regulating the passage of air by the lower valve to the receptacle to prevent a partial vacuum therein 95 as the lubricant is withdrawn.

5. A device of the kind described, comprising a suitable receptacle having a duct formed therein, an adjustable valve for controlling the duct, a downwardly extending part provided with two chambers, one arranged below the other, each having valve seats formed therein, and a passage connecting the two chambers, in combination with a valve arranged to coöperate with the valve seat in the upper chamber, provided with a stem passing through said passage, a conical part located within the lower chamber and adjustably secured to the stem, said conical part being provided with one or more openings therethrough extending from the upper face thereof to a point downward therefrom, a valve arranged to coöperate with the valve seat in the lower chamber, means for connecting the conical part to said lower valve, 120 125 130

and means for regulating the vaporization of the lubricant after it has passed the last named valve.

6. A device of the kind described comprising a suitable receptacle having a duct formed therein, a valve controlling said duct, a downwardly extending neck provided with two chambers, one arranged below the other, a passage connecting the two chambers, each of said chambers being provided with a valve seat, in combination with a valve arranged to coöperate with the valve seat in the upper chamber, and provided with a stem passing through the passage, a conical part having drip openings formed therein located in the lower chamber and adjustably secured to the valve, a second valve having one or more openings therethrough arranged to coöperate with the valve seat in the lower chamber, and means for connecting the conical part to the second valve, whereby the two operate in unison, said receptacle and neck having also formed therein a second duct extending downward from the receptacle into the opening in the neck, an air tube connected to the upper part of said duct, and extended to a point near the top of the said receptacle, whereby as the device is operated air may pass through said last mentioned duct and pass to the oil receptacle.

7. A device of the kind described comprising a suitable receptacle, having formed therein a duct, a chamber below the duct with a second chamber below the first, an adjustable valve controlling the duct, said first chamber having a valve seat seating downwardly, and the second chamber provided with a valve seat seating upwardly, in combination with a valve arranged to coöperate with the valve seat in the first chamber, provided with a stem extending into the second chamber, a conical part provided with drip openings located in the second chamber adjustably secured to the stem, a valve arranged to coöperate with the valve seat in the second chamber, and means for connecting the conical part of said last mentioned valve, whereby the two will operate in unison.

8. In a device of the kind described, a valve mechanism comprising a valve pro-

vided with a face seating downwardly, a stem extending therefrom, in combination with a conical part extending downwardly 55 and adjustably connected to the stem.

9. In a device of the kind described, valve mechanism, comprising a valve provided with a face seating downwardly, a stem extending therefrom and a conical part having 60 its base connected to the stem, in combination with a second valve seating upwardly, and means connecting said second valve to the conical part.

10. In a device of the kind described, a 65 valve mechanism comprising a valve provided with a face seating downwardly, a downwardly extending stem therefrom, a conical part having its base adjustably secured to the stem, in combination with a 70 second valve provided with a face seating upwardly, and having formed therein a series of openings extending therethrough, and means for connecting said second valve to the conical part.

11. In a device of the kind described, a valve mechanism comprising a valve provided with a face seating downwardly, a stem extending therefrom, a conical part adjustably secured to the end of the stem, 80 said conical part having drip openings extending from its upper surface downward, in combination with a second valve, provided with a face seating upwardly, said valve having a series of openings therethrough, and means for connecting said second valve to the conical part, substantially as described.

12. A lubricating device comprising a suitable receptacle having formed therein a 90 duct, and below the duct a valve chamber, and means for controlling the passage of fluid through the duct, in combination with a gravity valve mechanism arranged in the chamber normally maintained in its lower- 95 most position, and a perforated removable plate arranged below the valve.

In testimony whereof, I have hereunto signed my name in the presence of two subscribing witnesses.
